No. 37,490.

Patented July 11, 1905.

UNITED STATES PATENT OFFICE.

CHARLES E. DURYEA, OF READING, PENNSYLVANIA.

DESIGN FOR A CARRIAGE-BODY.

SPECIFICATION forming part of Design No. 37,490, dated July 11, 1905.

Application filed May 24, 1905. Serial No. 262,090. Term of patent 14 years.

To all whom it may concern:

Be it known that I, CHARLES E. DURYEA, a citizen of the United States, residing at Reading, in the county of Berks and State of Pennsylvania, have invented a new, original, and ornamental Design for Carriage-Bodies, of which the following is a specification, reference being had to the accompanying drawing, forming part thereof.

The figure is an elevation of a carriage-body, showing my new design.

I claim—

The ornamental design for a carriage-body, as shown.

CHARLES E. DURYEA.
